H. J. MAYNARD

GLOBE BRACKET FOR INCANDESCENT LAMPS

Filed Feb. 21, 1922

UNITED STATES PATENT OFFICE.

HARRY J. MAYNARD, OF YONKERS, NEW YORK.

GLOBE BRACKET FOR INCANDESCENT LAMPS.

Application filed February 21, 1922. Serial No. 538,257.

To all whom it may concern:

Be it known that I, HARRY J. MAYNARD, a citizen of the United States, residing in Yonkers, in the county of Westchester and 5 State of New York, have invented certain new and useful Improvements in Globe Brackets for Incandescent Lamps, of which the following is a specification.

My present invention relates to an improvement in a globe holding attachment for lamps, more especially for incandescent lamps, and has to do with the provision of means on Mazda lamps of well known type, such as is known as the P. S. type, in which 10 said lamps are provided with a distinctive neck portion which merges into the bulb or globular portion.

The main object of the invention is to provide a support or frame that may be affixed to a lamp of the foregoing type, and 15 adjustably mounted for holding a globe or the like in position surrounding said lamp, and to hold a reflector in position for co-operating with the globe to diffuse through 20 the globe light having its source in the lamp, whereby a light of different color effect from the normal light of the lamp is diffused through the globe, thus enabling 25 the color effect of any lamp to be changed 30 as desirable, the device being especially effective for window display, bill board lighting, and show or advertising purposes generally.

Another object of my invention is to so 35 construct a frame for such purpose that it may be readily detached from such lamp when the lamp is burned out and affixed to a renewal of such lamp.

Another object of my invention is to provide a simple frame structure that may be 40 quickly attached and detached and when mounted in operative position is so held as to prevent short circuiting through contact with the metal parts of the socket or associated structures.

Another object of my invention is to provide resilient means on said frame whereby 45 the frame or holder may adjustably adapt itself to the variation of dimensions on such 50 lamps, when such occur.

The foregoing and other capabilities will appear from the subjoined specification.

In the drawings appended, Fig. 1 is a 55 side elevation of my device, partly in section, applied to a lamp of the type described.

Fig. 2 is a plan view thereof with the reflector removed, and

Fig. 3 is a plan view of one of the associated frame holding and locating parts.

My invention consists of a plurality of 60 metal clips 4, in the present instance three such clips, equally spaced apart, see Fig. 2, the same being so formed at the bottom as to have a plurality of globe gripping means 5 bent to any suitable globe-rim gripping 65 shape, but preferably as shown. The three spring-metal clips 4 are rigidly affixed to an annular ring 1, so that they resiliently depend therefrom. The said metal ring 1 is of sufficiently large diameter to freely fit 70 over the neck of a P. S. Mazda type incandescent globe so as to facilitate removal and positioning of my device and to provide a certain desired amount of clearance therebetween.

Midway on each of the downwardly depending spring metal clips 4 there are located indented or raised, bent-out portions or shoulders 6 which form seats into which is fitted an annular, coiled, endless spring 2, 75 which performs the function of holding the said clips with a firm, resiliency grip against the lamp at the desired point, for thereby supporting the clips, the spring 2 supplementing the natural resiliency of the grips 5. 80

The lower end of said grips 5 are flared outwardly so as to conformably engage the rim 8 of any type of desired colored globe or light modifier 7, by gripping the edge thereof, as indicated in Figs. 1 and 2. 85

In order to prevent the metallic band 1 from rising upwardly when in position on the globe, and thereby endanger the apparatus and affiliated circuits by reason of short circuiting through contact with the conductive parts of the lamp socket, I have provided a three-arm anchorage piece 11, shown in Fig. 3 in plan view, and also in position over the sprue 14 of the lamp 3, Fig. 1, and it will be noted that each of 90 said arms of the said anchorage element 11 is provided with a hole 12 whereby a preferably resilient tie 9 is engaged in each of said holes 12, the upper ends of said ties being engageable by hooking, or other suitable manner, to the annular retention element 2.

The foregoing structure is fully shown in Fig. 1 in which the globe and frame are fully shown and a coating reflector 15 is 105

shown in partial section. The ties 9, in the present instance, owing to the desire for a resilient, self accommodating, semi-rigid holding means, are made in the form of thin wires having a coil portion 9' intermediate of their ends whereby it may resiliently and conformably engage to hold the lamp portion 3 in proper operative position relative to the general frame structure, or vice versa.

5 In operation, in the mounting of my device upon a lamp of the type described, one of the ties 9 may be released or unhooked from the hole 12 of the anchor 11 and the anchor thereafter lifted over the sprue 14 of the lamp 3, and, with the globe 7 having been previously removed by unhooking, the complete frame 4 may be entirely slipped upwardly from the lamp, but still in connected self-assembly.

10 In placing the device over a lamp renewal, the reverse operation takes place, and after the frame 4 has been seated downwardly upon the neck of a lamp, as shown in Fig. 1, the unhooked tie member 9 may be again engaged with the element 11 and the frame is then lifted in operative position ready to receive its associated light modifying globe or shade, by clipping the same along its upper edge 8 in the grips 5.

15 When it becomes desirable to apply reflectors or the like to a lamp associated with my structure, any reflector, such as 15, shown in section in Fig. 1, as a conical reflector, may be slipped downwardly over the clips 4 until it comes into engagement with the upper portion of the hooks 5 and by reason of the frictional and resilient engagement of the upper edge 16 of the truncated cone shaped reflector with the three flat surfaces F of the clips 4, the reflector will be held in operative relation to the globe, thereby intensifying the light in the desired direction and preventing the escape of white light, when so desired.

20 It will be noted that the globe 8 and reflector 15 when in operative relation envelope the lamp on all its sides and one end, and provide an enveloping case for the lamp substantially conforming to the shape thereof, the reflector enveloping the lamp on all its sides from a point near the upper end of the neck of the lamp to a point substantially midway of the length of the lamp, and the globe enveloping the lamp on all its sides and its end from said midway point. The globe and reflector being spaced away from the lamp, the heat of the lamp confined in the space formed between the exterior of the lamp and the interiors of the globe and reflector is permitted to escape from the opening at the upper edge 16 of the reflector.

without departing from the spirit of the invention, or exceeding the scope of the appended claims.

What I claim and desire to protect by Letters Patent is:

1. A light diffusing device for electric lamps, said device comprising a globe; a reflector; means comprising a band around the upper end of the neck of the lamp and a plurality of arms secured at their upper ends to said band and extending in the line of the neck for substantially the length of the neck, the arms having means engaging the sides of the lamp at the lower end of the neck for supporting said means on the lamp and maintaining said band and the upper portions of the arms spaced away from the sides of the neck, the arms below said engaging means being bent outwardly and provided at their free ends with means for engaging the upper edge of the globe and the lower edge of the reflector for supporting the globe and reflector around the lower portion and neck of the lamp in positions spaced away from the sides of the lamp; and resilient means for retaining in engagement with the sides of the lamp, said means engaging the sides of the lamp at the lower end of the neck.

2. A light diffusing device for electric lamps, said device comprising a globe; a reflector; means comprising a band around the upper end of the neck of the lamp and a plurality of arms secured at their upper ends to said band and extending in the line of the neck for substantially the length of the neck, the arms having means engaging the sides of the lamp at the lower end of the neck for supporting said means on the lamp and maintaining said band and the upper portions of the arms spaced away from the sides of the neck, the arms below said engaging means being bent outwardly and provided at their free ends with means for engaging the upper edge of the globe and the lower edge of the reflector for supporting the globe and reflector around the lower portion and neck of the lamp in positions spaced away from the sides of the lamp; resilient means for retaining in engagement with the sides of the lamp said means engaging the sides of the lamp at the lower end of the neck; and means cooperating between said resilient means and the lower end of the lamp for preventing upward movement of said arms and band.

3. A light diffusing device for electric lamps and comprising a globe; a reflector; supporting means comprising a band arranged around the neck of the lamp and resilient members on said band having end portions engageable with the upper edge of the globe; means for compressing the resilient members for maintaining the end portions thereof in engagement with the

130

upper edge of the globe; and means cooperating between the compressing means and the lower end of the lamp for preventing upward movement of said supporting means.

5. 4. A light diffusing device for electric lamps and comprising a globe; a reflector; a band arranged around the neck of the lamp; resilient arms on said band having shoulders about midway of their length and having grip ends engageable with the upper edge of the globe; and a helix spring ring around said arms under said shoulders; the reflector being supported at its lower edge 10 on said grip ends adjacently to the upper edge of the globe and spaced away at its upper edge from the neck of the lamp by said band.

5. In a globe and reflector support for 20 electric lamps, a globe open at its top and closed at its bottom and having an outwardly flaring upper edge, the lower portion of the lamp being received in the globe; a band loosely encircling the neck of the 25 lamp; a plurality of spring clips attached at one of their ends to said band and having outwardly bent portions forming shoulders about midway of their length and having grips at their free ends; compressing means 30 arranged around the clips under said shoulders for pressing the clips against the lamp to support the clips on the lamp the grips of the clips being engageable over the flaring edge of the globe for supporting the 35 globe; a reflector arranged over said clips and engaging at its lower edge the backs of the grips of the clips for cooperating

with the globe to provide a combined globe and reflector for the lamp; and means cooperating between said compressing means 40 and the sprue of the lamp for holding the lamp in operative relation to the combined globe and reflector.

6. In a globe and reflector support for electric lamps, a globe open at its top and closed at its bottom and having an outwardly flaring upper edge, the lower portion of the lamp being received in said globe; a band loosely encircling the neck of the lamp; a plurality of spring clips 45 attached at one of their ends to said band and having outwardly bent portions forming shoulders about midway of their lengths and having grips at their free ends; a helix spring ring arranged around the clips 50 under said shoulders for pressing the clips against the lamp to support the clips on the lamp the grips of the clips being engageable over the flaring edge of the globe for supporting the globe; a reflector of truncated 55 cone shape arranged over said clips and engaging at its lower edge the backs of the grips of the clips for cooperating with the globe to provide a combined globe and reflector for the lamp; an anchorage piece 60 engaging the sprue of the lamp; and resilient means cooperating between the sprue of the lamp and the helix spring ring for holding the lamp in operative relation to the combined globe and reflector.
